UNITED STATES PATENT OFFICE.

EUGENE T. TURNER, OF NEW YORK, N. Y., ASSIGNOR, BY MESNE ASSIGNMENTS, TO AMERICAN PLAYER ACTION COMPANY, OF NEW YORK, N. Y., A CORPORATION OF NEW YORK.

PIANO-PLAYER.

1,169,440.

Specification of Letters Patent. Patented Jan. 25, 1916.

Application filed February 8, 1912. Serial No. 676,254.

To all whom it may concern:

Be it known that I, EUGENE T. TURNER, a citizen of the United States, and a resident of the city, county, and State of New York, have invented new and useful Improvements in Piano-Players, described in the following specification.

In most of the piano players in use it is customary to control the tempo by means of 10 a hand operated lever by which the operator can retard or accelerate the action or can stop it in order to secure a rest of any desired duration. This, however, makes the phrasing of the music dependent upon the 15 skill of the operator.

This invention aims to provide certain improvements in mechanism for automatically or mechanically controlling the tempo, that is the rate of succession of the notes in 20 player-pianos and similar instruments; and especially to provide for automatically causing a full stop and again starting the music when such a rest is desirable for securing proper expression or phrasing.

25 The accompanying drawings illustrate an apparatus embodying the invention.

Figure 1 is a fragmental elevation of a portion of a piano player equipped with a tempo-controller and a stopping and starting mechanism. Fig. 2 is a fragmental elevation of the tracker-board of Fig. 1. Fig. 3 is a plan, partly in section, of the controller and a portion of the restarting mechanism. Fig. 4 is a vertical section approximately on the line 4—4 of Fig. 3. Fig. 5 is an enlarged detail of a pneumatic used in connection with the restarting mechanism. Fig. 6 is a vertical section of the same, on a plane parallel with Fig. 5. Fig. 40 7 is a section on the line 7—7 of Fig. 3. Fig. 8 is a fragment of the side of the music sheet. Fig. 9 is a front elevation of the principal parts of a player in which my improvements are incorporated.

45 Referring to the embodiment of the invention illustrated, spools 1 and 2 carry the opposite ends of a perforated music sheet 3. Between the spools is a tracker-board 4 having openings in its face over which the music 50 sheet passes. The perforations in the music sheet by opening and closing the several perforations in the tracker-board communicate in any usual or suitable way with mechanism for operating the keys or the action of

the piano or other instrument, and causing 55 such instrument to play the desired music.

Suitable winding and rewinding mechanism, indicated as a whole by the numeral 5, connects the spools with a motor 6 which may be of the usual type in which the exhaustion of air causes the driving of the shaft 60 of the winding and rewinding mechanism.

The air from the motor 6 is exhausted through a tube 7 which leads to a compartment 8 which communicates with an adjacent compartment 9 through a port 10. From the compartment 9 a tube 11 leads to any suitable mechanism for exhausting the air. A valve 12 controls the opening through the port 10 and has a stem 13. An 70 expansion spring 14 holds the valve 12 normally off its seat. The stem 13 extends through the compartment 9 and outside of the same adjacent to a bellows 15 which has an arm 16 secured to its movable member, 75 the arm 16 being in line with the projecting end of the valve stem. A passageway 17 is provided between the compartment 9 and the bellows 15 and a plate 18 covers said passage and is provided with a small bleed 80 hole through which communication is maintained while the passage of air is retarded owing to the small size of the hole.

When air is withdrawn from the compartment 9 a suction is exerted on the bellows 85 15 through the bleed hole in the plate 18. This causes the collapsing of the bellows which, through the arm 16 depresses the valve 12. By admitting varying quantities of air to the bellows 15 the movement thereof 90 under the suction referred to is controlled and consequently the position of the valve 12 and the suction exerted upon the motor 6 and the speed of such motor is also controlled.

The provision for admitting varying 95 quantities of air to the bellows, and thus causing the motor to operate at varying speeds is as follows: The tracker-board is provided, preferably at one end of the line of perforations, with an opening 19 of triangular shape which communicates through the tube 20 (and passages hereinafter described) with the bellows 15. In the portion of the music sheet which passes over the opening 19 is an undulating line of perforations 21 which admit more or less air to the tube 20 as they pass over a broader or narrower portion of the opening 19 in the 100 105

tracker-board, as shown by dotted lines in two extreme positions in Fig. 8. When it is desired to come to a full stop the line of perforations is either discontinued or is carried out of line with the opening 19. Various other provisions in the tracker-board and music sheet may be adopted for securing the admission of varying quantities of air; several of such provisions being shown 10 in my previous applications for Patent Nos. 649,850 and 649,851, filed Sept. 18, 1911. The tube 20 passes from the tracker-board to a casing 22 and thence a tube 20^a communicates with a passage 20^b through the fixed 15 member of the bellows 15.

If, however, air is not admitted to the bellows 15 before the latter has caused the seating of the valve 12, then the closing of the port 10 by the valve will prevent further 20 suction upon the motor and the motor will stop, notwithstanding the continued application of the motive power or suction in the tube 11; there being no further advance of the music sheet, no further air will be 25 admitted to the tube 20 and unless special provision is made for admitting air to the bellows 15 after the motor has stopped the motor will remain idle. Restarting mechanism is, therefore, provided whereby air is 30 admitted to the bellows after the stopping of the motor, as follows. The passage in the casing 22 communicates with a chamber 23 adjacent thereto and adapted to open directly into the atmosphere or to be closed 35 by a hinged cover 23^a. The cover is normally closed by a spring 24 bearing on the top of it. The free end of the cover extends beyond the side of the casing 22 and into the path of an arm 27 on the movable mem- 40 ber of another bellows 25 in which is a spring 26 for distending it. When the bellows 25 is expanded therefore the cover 23^a is lifted and air is admitted freely through the casing 22 and the tube 20^a to the bellows 45 15 whose expansion causes the movement of the motor. Through the fixed member of the restarting bellows 25 is a passage 28 leading into a chamber in a casing 27^a which is connected with a re-starting supply of air 50 and which also communicates through a tube 30 with a chamber in a casing 31 opening through a port 32 into a tube 33 which leads to a vacuum chest 33^a communicating by a tube 47 with the usual mechanism for 55 maintaining a vacuum. A valve 34 controls the port 32 and carries a stem 35 which passes through to the outside of the casing 31.

The casing 31 is mounted on the outside 60 of a pneumatic comprising a vacuum chamber 36 (Fig. 6) and a diaphragm chamber 38 separated from the vacuum chamber 36 by a diaphragm 37. The chambers 36 and 38 are in communication through a small bleed hole 39. The diaphragm 37 bears against

the inner end of a valve stem 40 carrying valves 41 and 42 which control respectively the ports 43 and 44 from the vacuum and from the atmosphere. A passage 45 communicates with the space between the ports 70 43 and 44 and leads therefrom to a bellows 45^a which has an arm 46 (Fig. 5) engaging the valve stem 35.

Leading from the diaphragm chamber 38 is a passage 48 which communicates with 75 tubing 49 which has an auxiliary releasing opening 50 in the tracker-board, preferably at the end opposite the opening 19, so that it comes under the opposite margin of the music sheet and this margin of the music 80 sheet is provided with one or more releasing perforations 51 adapted to register with the opening 50 and located at points where the line of perforations 21 is discontinued or runs off the opening 19. 85

Now when the sheet is advanced to such a position as to close the opening 19 it simultaneously opens the opening 50 and admits air through the tube 49 into the diaphragm chamber 38 which causes a lifting of the 90 diaphragm 37 and the valves so as to bring the bellows 45^a into communication with the vacuum chamber 36, thus closing the bellows and closing the valve 34 so as to prevent any suction through the tube 30. The 95 suction which normally holds the restarting bellows 25 inoperative is thus cut off when the port 50 in the tracker-board is open. Air is thereupon admitted (by means hereinafter described) into the chamber 27^a and 100 through the passage 28 into the restarting bellows 25. The spring 26 will gradually expand the restarting bellows causing the lifting of the cover 23^a and the admission of air directly from the atmosphere to the 105 chamber 23 and through the tubing 20^a into the main bellows 15 allowing the latter to expand. This in turn will open the port 10 and allow the vacuum chamber 9 to exert a suction through the chamber 8 and tubing 110 7 upon the motor 6 so as to start the latter. The controlling perforations upon the note sheet will then come into play and simultaneously the advance of the sheet will close the restarting opening 50. Air being then 115 cut off from the tubing 49 and from the diaphragm chamber 38 the balance will soon be restored through the bleed hole 39, between the vacuum chamber 36 and the diaphragm chamber 38, and the valves 41 and 42 will be lowered. Atmospheric communication will then be established with the bellows 45^a and the latter will expand and withdraw the valve 34 so as to open the port 32. The suction through the tube 33 will then be communicated through the tubing 30 and chamber 27^a to the restarting bellows 25, so as to collapse the latter and to allow the cover 23^a to close. The regular 120 controlling communication between the 130

tubes 20 and 20^a will thus be re-established, whereby the undulating perforations of the note sheet will vary the quantity of air admitted to the controlling bellows 15, and the 5 speed of the motor will be controlled as desired.

For admitting air to the restarting bellows 25 a bleed hole 29 (Fig. 7) may be made into the chamber 27^a. This will insure 10 a restarting operation in a definite time. Preferably, however, means are provided for admitting air to the chamber 27^a to restart the operation after a time whose length is controllable automatically by the 15 music sheet. This controllable admission of air may be used in connection with the bleed hole 29 or may be used without the latter. For the purpose of admitting the restarting air at a variable rate a tube 52 20 communicates with the chamber 27^a and with a restarting opening 53 in the tracker board. The music sheet 3 is provided with a line of perforations 54 which register with the aperture 53 in the tracker board, these 25 holes 54 being larger or smaller so as to admit air more or less rapidly to the chamber 27^a to restart the motor. The restarting perforations 54 (whereby air is admitted to bellows 25 and, through the expansion of 30 this bellows and the lifting of the valve 23^a, to the bellows 15 to cause the opening of the valve 12 and the restarting of the motor) should register with the releasing perforations 51 in the sheet (whereby air admitted 35 to the diaphragm chamber 38, Fig. 6, causes the closing of the bellows 45^a and the closing of the valve 34, Fig. 5, stopping the suction on the tube 30 and thus releasing the bellows 15.) When a stop occurs in the music, 40 therefore, the apertures 50 and 53 in the tracker board are both opened. The suction which normally closes the restarting bellows 25 is cut off and simultaneously atmospheric air is admitted through the restarting perforations 54 (or through these and the bleed hole 29) at a rate determined by the size of the perforation 54; and the music will commence again after the desired interval of rest.

50 Fig. 9 shows the self-contained means for controlling the tempo as described, the whole being in place in a piano player of known construction. On the same level with the spool box are carried the motor 6 and the 55 casings and bellows above described. The tubes 11 and 47 lead downward to the wind chest or suction chamber 55 which is arranged in the form of three longitudinal chests communicating with each other at 60 their ends. These chests are in communication through a large pipe 56 with a regulator 57 in which suction is maintained by means of bellows 58, 58' operated by pedals 59. Details of the mechanism are omitted; 65 not being pertinent to the present invention,

the novelty of which is in the tempo-controlling mechanism, as described.

In various prior patents for the synchronizing of two musical and other instruments it has been proposed to regulate the speed of 70 one instrument from the other. In the present invention the instrument to be regulated is self-contained; that is the regulation is without reference to the speed or the stopping and starting of any other instrument. 75

Though I have described with great particularity of detail a specific embodiment of my invention, yet it is not to be understood therefrom that the invention is restricted to the particular embodiment described. Various modifications thereof in detail and in the arrangement of the parts may be made by those skilled in the art without departing from the invention.

What I claim is:—

1. A piano player adapted to cause the playing of music under control of an advancing note sheet, said player itself including means for stopping the advance of the sheet at a predetermined point and means 90 for automatically continuing the same forward from the same point at which it stopped.

2. A piano player in which the playing is controlled by the passage of a perforated 95 music sheet, in combination with means controlled by said sheet for stopping its own movement and for continuing said movement from the point at which it stopped and in the same direction in which it was previously 100 moving.

3. A piano player including in combination, a single note sheet, a motor for moving said note sheet and means controlled by said single note sheet for automatically starting 105 its said motor.

4. A piano player including in combination, a single note sheet, a pneumatic motor for moving said note sheet, means controlled by said single note sheet for automatically 110 closing an air passage to stop its said motor and for reopening said passage.

5. A piano player including in combination a note sheet, a motor, a bellows which controls the speed of said motor, means controlled by said note sheet for cutting off air from said bellows to cause the stoppage of the motor and means for admitting air to said bellows to cause the restarting of the motor.

6. A piano player including in combination a motor, a main bellows which controls the speed of said motor, means for cutting off air from said bellows to cause the stoppage of the motor, and a restarting bellows 125 adapted to cause the admission of air to said main bellows.

7. A piano player including in combination, means for advancing a note sheet, means for stopping the advance of said sheet 130

- at a predetermined point and means for automatically continuing the same forward from the point at which it stopped after a controllable interval of time.
- 5 8. A piano player in which the playing is controlled by the passage of a perforated sheet, in combination with means controlled by said sheet for stopping its own movement and for continuing such movement after a 10 controllable interval of time from the point

at which it stopped and in the same direction in which it was previously moving.

In witness whereof, I have hereunto signed my name in the presence of two subscribing witnesses.

EUGENE T. TURNER.
